F. L. McCARTY ET AL

AUTOMATIC SAFETY BRAKE

Filed Sept. 3, 1924

Patented May 12, 1925.

1,537,541

UNITED STATES PATENT OFFICE.

FRANK L. McCARTY AND ALFRED R. ANDERSEN, OF ROCK SPRINGS, WYOMING.

AUTOMATIC SAFETY BRAKE.

Application filed September 3, 1924. Serial No. 735,609.

To all whom it may concern:

Be it known that we, FRANK L. McCARTY and ALFRED R. ANDERSEN, citizens of the United States, residing at Rock Springs, in the county of Sweetwater and State of Wyoming; have invented certain new and useful Improvements in an Automatic Safety Brake, of which the following is a specification.

10. Our invention relates broadly to vehicles, and more particularly to an emergency brake or check for mantrips used in coal mines.

One of the objects of our invention is to 15 provide an automatic safety brake mechanism operative upon the breaking of a cable in a trip or train of cars for chucking the car wheels and bringing the car to a stop, thereby preventing a runaway with its inherent dangers.

Another object of our invention is to provide a simplified and practical construction 20 of chuck for a car wheel with means for suspending the chuck from the vehicle body in such manner as to become immediately operative between the car wheels and the rails for preventing relative movement of the cars with respect to the rails.

Still another object of our invention is to 25 provide a safety device particularly adapted for said railway cars and mine cars which are required to ascend or descend grades of large degrees comprising a chuck in the form of a shoe adapted to enter between the tread 30 of the car wheel and the rail at the same time that auxiliary mechanism is operated to sand the rail for increasing the friction between the chuck and the rail surface.

Still another object of our invention is to 35 provide a practical construction of emergency brake or check for mantrips embodying a small number of rugged parts normally held in inoperative position by a cable extending through a series of cars and arranged to become immediately operative 40 upon the parting of the cable due to accidental separation of the cars whereby such cars are brought to a standstill.

Our invention will be more clearly understood from the following specification and by reference to the accompanying drawings, in which:

Figure 1 is a side elevation of one end of

a car equipped with the automatic safety brake of my invention with a portion of the 55 car broken away to show the interior mounting of the brake mechanism; Fig. 2 is a view of a portion of the car showing the safety brake mechanism normally held out of engagement with the car wheel; Fig. 3 60 is a partial cross-sectional view taken on line 3—3 of Fig. 1 and showing the arrangement of the safety brake mechanism with relation to the car wheel; Fig. 4 is a cross-sectional view taken through the chuck or 65 shoe which engages the car wheel; Fig. 5 is a fragmentary view of the spring pressed valve which controls the delivery of sand to the rail when the chuck becomes engaged 70 between the rail and wheel; and Fig. 6 is a diagrammatic view illustrating the arrangement of the automatic safety brakes upon a plurality of mine cars ascending a steep grade.

Referring to the drawings in detail, reference character 1 indicates a rail upon which the car is arranged to operate. Reference character 2 shows the chuck or shoe arranged to slide beneath the car wheel upon the breaking of cable line 3 as will be hereinafter described. The brake shoe 2 is provided with a lining 4 of belting or other material to provide a high frictional contact with the surface of the rail 1. The shoe 2 has a pressed metal or cast block 5 thereon which engages with the tread surface of car wheel 6. The body of the car has been indicated generally at 7. While we have represented the automatic safety brake as applied to a mine car, it will be understood that it may be applied to street railway cars where occasion demands. The wheel 6 is carried upon axle 8 adjacent which the brake mechanism is mounted.

A shoe similar to that represented at 2 may be mounted on each side of the car 1 normally raised out of engagement with the tread of wheel 6 as indicated in Fig. 2. The mechanism comprises a shaft 9 extending laterally of the car with a vertical extension 10 in the form of a T centrally positioned along shaft 9 within the car body 7. The shaft 9 has a portion 11 disposed at an obtuse angle with respect to the laterally extending shaft 9, the shaft 9 terminating 100 in a portion 12 extending vertically or at

right angles to the shaft 9. A journal 14 is provided on the extremity of portion 12 of shaft 9 in which is pivoted the end 15 of the shoe 2. A coil spring 16 is secured at a point 17 beneath the car body and attaches at a point 18 to the block 5 on shoe 2. The spring 16 normally tends to hold the brake shoe 2 off of the rail 1 and out of engagement with the tread of wheel 6 when the trip is in hoisting position. The shaft 9 is rotatably mounted in journal box 18 carried by car body 17 and is normally held forward by cable 3 secured to the short lever 10 of shaft 9 against the action of compression spring 19 normally tending to force lever 10 in such position that the brake shoe 2 will engage the wheel 6. The pressure of spring 19 is resisted by the pull of cable 3 in such manner that should cable 3 snap and thereby release lever 10 the spring 19 will have its potential energy converted into kinetic energy and expended against lever 10, forcing brake shoe 2 in a downward direction against wheel 16.

25 We provide a sand box 20 mounted adjacent the brake mechanism with a delivery tube 21 extending therefrom and a valve 24 actuated by plunger 22 and spring 23 interposed in the said delivery pipe. The spring 30 23 is normally depressed by reason of the abutting of the journal 14 against plunger 22 when the brake mechanism is in raised position. When however the cable 3 snaps and the brake shoe 2 is forced down, the 35 valve 24 opens and sand slides down delivery tube 21 and out through the delivery mouth 25 upon the rail 1.

In order to insure the aligning of the shoe 2 with the tread of the wheel 6 and the 40 surface of rail 1, we provide a guide member 26 co-extensive with the shoe or chuck 2. This guide member 26 has a U shaped flange extending downwardly as indicated at 28 adjacent the flange of the rail 1 and 45 upwardly as indicated at 29 in the direction of the flange 27 of the wheel 6. The distance between the sides 28 and 29 of the U shaped guide member 26 is substantially 50 greater than the width of the car wheel flange 27 so that the shoe 2 becomes centered in position beneath the tread of the wheel 6 with the frictional surface 4 bearing upon rail 1. To further insure against the displacement of the brake shoe from 55 the rail the lower surface of the brake shoe 2 is bent downwardly at an angle as represented by reference character 31 so that the entire shoe may be rigidly capped over the rail.

60 The arrangement of the emergency brake as described herein upon mine cars has been successfully embodied by us in mine operation. This system of brake cars insures safety against runaways. In case of 65 a coupling or a main cable breaking our

mechanism greatly reduces the danger of loss of life by a runaway car. Our mechanism finds particular application upon cars in a train of a plurality of cars. These cars often have to carry six men each and 70 ascend and descend at least a fifteen degree slope in a mine. In case of a break serious injury might result to these men. In our system the cable 3 extends through the several cars and normally is placed under 75 tension to hold brake shoe 2 away from the wheel 6. Should this cable 3 part as represented by reference character 3 in the dia- 80 grammatic view in Fig. 6 the shoe 2 is thrust under the wheel 6 which attempts to climb the inclined surface 5. At the same time sand will have been deposited on the surface of rail 1. The shoe 2 will have dropped in position upon rail 1 and become hooked against lateral displacement by 85 means of the hook shaped member 26 as heretofore described. The frictional under surface 4 of the brake shoe 2 added to the friction developed by the sand deposited simultaneously with the dropping of the 90 shoe 2 insures the car against running away.

While we have described our invention in certain particular embodiments it will be understood that we intend no limitations upon the invention other than those imposed 95 by the scope of the appended claims.

What we claim and desire to secure by Letters Patent of the United States is as follows:

1. An emergency brake for railway cars 100 comprising in combination with a car body, a wheel and a rail, a laterally extending shaft carried by said car body and mounted for limited rotative movement, a journal on one end of said shaft, a brake shoe pivotally 105 mounted in said journal, means for supplying sand to said rail, spring means for normally maintaining said brake shoe out of engagement with said wheel and rail and rendering said aforementioned means inoperative, separate spring means tending to 110 thrust said brake shoe to a position intermediate said wheel and rail and means for normally rendering said last mentioned spring means inoperative. 115

2. An emergency brake for railway cars comprising in combination with a car body, a rail, a wheel having a flange and a tread, a laterally extending shaft carried by said car body and mounted for limited rotative 120 movement, a journal on one end of said shaft, a brake shoe pivotally mounted in said journal, said shoe having a frictional surface and an angularly disposed portion adapted to fit upon said rail, means for sup- 125 plying sand to said rail, spring means for normally maintaining said brake shoe out of engagement with said wheel and rail and rendering said aforementioned means inoperative, separate spring means tending 130

to thrust said brake shoe to a position intermediate said wheel and rail and means adapted to be longitudinally severed for releasing said last mentioned spring means for positioning said shoe upon said rail

5 simultaneously with the delivery of sand thereon, said angularly disposed portion of

said shoe operating to prevent lateral displacement of said shoe with respect to said rail.

In testimony whereof we affix our signatures.

FRANK L. McCARTY.
ALFRED R. ANDERSEN.
